Attorney

UNITED STATES PATENT OFFICE.

FREDERIKA G. BELL, OF ST. PAUL, MINNESOTA.

KNITTING DEVICE.

1,351,016.

Specification of Letters Patent. Patented Aug. 31, 1920.

Application filed July 30, 1917. Serial No. 183,406.

To all whom it may concern:

Be it known that I, FREDERIKA G. BELL, a citizen of the United States, residing at St. Paul, in the county of Ramsey and State 5 of Minnesota, have invented certain new and useful Improvements in Knitting Devices, of which the following is a specification.

My invention relates to improvements in 10 knitting needles, its object being to provide improvements in connection with the needle which will allow the loops formed in knitting to be picked up by the needle with the same facility that the loops in crocheting 15 are picked up by the ordinary crochet hook and at the same time to provide an attachment which will not interfere with the continued knitting and the transfer of the loops from one needle to the other.

20 To this end my invention consists particularly of either providing a detachable hook member adapted to be removably secured upon one end of the knitting needle whereby it will be capable of use in picking up the 25 loops, said member being removable from the needles so as to be placed upon one of the other needles to convert said other needle into a pick-up needle, or, provide each knitting needle with a hook element 30 at one end, the other end of the needle being formed in the ordinary manner to allow the loops to be slipped therefrom in knitting.

In the accompanying drawings, forming 35 part of this specification

Figure 1 shows a pair of knitting needles having conoidal ends arranged in knitting position in connection with a flat piece of work, one of the needles being shown fitted with my improved attachment with the attachment shown in the act of picking up and forming a loop;

Fig. 2 is a detail view, partly broken away, of my improved attachment.

Referring to the drawings, A represents 45 an ordinary knitting needle having pointed work ends 2.

As shown best in Fig. 2, my attachment 50 consists of an extension member B formed at one end with a hook 4 and at the other end with a central opening 5 to receive the pointed end of the knitting needle. As shown, I preferably taper the inner end of the opening 5 to provide a close fit for the pointed end of the needle and provide the 55 opening with an elastic or other suitable lining 6 to grip the needle. In utilizing my

attachment, it is simply fitted over the end of the knitting needle to form an extension thereof, the attachment being placed upon that needle which is being used to pick up 60 and form the loops.

In knitting with the ordinary knitting needles, one of the needles serves as the pick-up needle, and as the pick-up needle receives the required number of loops, the 65 next needle becomes a pick-up needle and the operation of knitting is thus carried out. In consequence, with the knitting needle as ordinarily employed, the loops have a tendency to slip off the end of the pick-up needle 70 making it particularly difficult for the amateur to knit and this difficulty in connection with knitting has resulted in increasing the popularity of crocheting at the expense of 75 knitting on account of the ease of picking up the loops by the ordinary hook employed in crochet work. In crochet work, as will be understood, there is not the changing from needle to needle throughout the 80 crochet work operation but instead continued use of the same knitting member therefore making easy the use of a crochet hook.

By the use of my attachment, as will be 85 evident, I am enabled to form each needle into a pick-up hook during the particular time that it is being used as the pick-up knitting member and at the same time restore the needle to condition as a straight, unhooked needle when it has received the desired number of stitches, thus allowing the 90 loops to be removed therefrom in the continued operation.

I do not restrict myself to the particular 95 construction of attachment shown because, as will be evident, different methods may be employed to removably support the hook member upon the end of the needle. I define the scope of my invention in the following claim.

I claim:

An attachment for knitting needles comprising a sleeve having a hook at one end, and adapted to be slipped over and frictionally retained on the end of the needle. 105

In testimony whereof I affix my signature in presence of two witnesses.

FREDERIKA G. BELL.
